EX

UNITED STATES PATENT OFFICE.

WALTER J. GADSBY, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 12,468, dated September 13, 1881.

Application filed August 16, 1881. Term of patent 34 years.

To all whom it may concern:

Be it known that I, WALTER J. GADSBY, a subject of the Queen of Great Britain, residing at Boston, in the county of Suffolk and State of Massachusetts, have invented a certain new and original Design for Carpets, of which the following is a specification.

The design is fully illustrated in the accompanying photograph, forming part of this specification.

The design consists of the light ground-centers A A' and the dark ground-centers B B', relatively arranged as shown, and ornamentation consisting of foliage and flowers surrounding and partially overhanging said ground-centers.

I claim—

The design for a carpet, substantially as herein shown and described.

In testimony whereof I have signed my name to this specification, in the presence of two subscribing witnesses, this 10th day of August, A. D. 1881.

WALTER J. GADSBY.

Witnesses:

WILLIAM SCHMIDT,
DAVID McNAIR.
